UNITED STATES PATENT OFFICE

IRVIN M. CONWAY AND HERSCHEL H. HAROLD, OF INDIANAPOLIS, INDIANA, ASSIGNORS TO JOURNAL BOX SERVICING CORPORATION, OF INDIANAPOLIS, INDIANA, A CORPORATION OF INDIANA

USED JOURNAL BOX WASTE ROLL OPENER

Application filed May 15, 1931. Serial No. 537,666.

This invention relates to the art of loosening rolls of waste which have been used in the packing of journal boxes of locomotives, freight cars, passenger cars, and other like vehicles.

Waste taken from journal boxes is now commonly washed out in hot oil and during such washing operations the waste is preferably pulled apart slightly and opened up to permit foreign matter such as sand, Babbitt metal, carbon and the like to be separated from the waste. It is a common practice to pack journal boxes of the type above indicated with a roll of waste around the back part of the box. This roll is originally formed from new waste and is wrapped about a rapidly revolving spindle and has twine wrapped around the roll thus formed to hold it in shape. When the journal boxes are cleaned out and the old waste removed therefrom, these packing rolls of course are taken out with the other loose waste and upon the waste containing such rolls being dumped into a washing machine it has been practically impossible to open up these rolls within the washing machine and clean the waste therein.

It is the primary purpose of this invention to provide means for opening or loosening such packing rolls of waste prior to the roll being placed in a washing machine.

An important object of the invention is not only to open up the roll but to open the roll in such a manner that the fibers of the waste are not cut more than is necessary so as to prevent the forming of short ends as much as possible.

Another important object of the invention is to provide mechanical means for so opening the packing rolls whereby the operation may be quickly performed with the minimum expenditure of time and labor.

These and other objects will become apparent in the following description of the invention as illustrated in the accompanying drawings, in which

Fig. 1 is a fragmentary side elevation of a machine employing our invention;
Fig. 2, a top plan view of the machine;

Fig. 3, an end elevation of the machine; and

Fig. 4, a vertical diametrical section on the line 4—4 in Fig. 1.

Like characters of reference indicate like parts in the several views in the drawings.

Upon a suitable base 10 we mount the rollers 11 and 12 to have their axes of rotation parallel. The roller 12 is provided with bearing blocks 13 at each end of its supporting shaft 14 which may be adjusted to carry the roller 12 toward or away from the roller 11 whereby the space therebetween may be varied.

The roller 12 is essentially a cylinder having two annular grooves 15 and 16 turned therein with the side walls of the grooves sloping outwardly and upwardly from the bottoms thereof. The two grooves are thus separated by a central ring 17 the sides of which slope outwardly and downwardly to the bottoms of the grooves. The bottoms of the grooves 15 and 16 are preferably formed to have transverse corrugations therearound.

The roller 11 is substantially the same as the roller 12 with the exception that in place of the central dividing ring 17 there is substituted therefor a circular knife 18. In order to prevent having to make the entire roller 11 out of material suitable to maintain a cutting edge, the roller 11 is built up in section, Fig. 4, to have the knife 18 gripped between the sections 19 and 20 thereof by means of the through bolts 21. The bottoms of the grooves on either side of the knife 18 are also preferably corrugated transversely in order to present a roughened surface.

Below the rollers 11 and 12 supported by the frame 10 we mount the drive shaft 22 which is connected by the gear 23 with the parallel counter-shaft 24. The shaft 22 is driven through the chain 25 and from each of the shafts 22 and 24 drive chains extend to sprocket wheels on the shaft 14 of the roller 12 and the shaft 26 of the roller 11 whereby one roller is driven in a clockwise direction and the other roller in the opposite or counter-clockwise direction so that the relative travel between the rollers is downwardly.

We mount a hopper 27 immediately above the rollers to have its lower end discharging to between the rollers. In operating the structure above described a packing roll 28 here shown as having the twine 29 wrapped therearound is dropped into the hopper 27 which is so shaped as to direct the roll 28 by one end thereof centrally to between the rollers 11 and 12. Upon the roll 28 coming in contact with the rollers, it is drawn therebetween and compressed over the ring 17 which causes the twine 29 about the roll to be placed under considerable tension as the knife 18 revolves across the twine during the travel of the roll 28 downwardly between the rollers. The roller 12 is suitably adjusted in relation to the roller 11 to have the proper distance therebetween whereby the packing roll 28 is compressed around and pulled back over the ring 17 sufficiently to supply the necessary tension on the twine 29 but not permitting the knife 18 to cut down into the roll a sufficient distance to cut the fibers of the waste itself to any great extent. Since the twine 29 is thus presented to the knife under considerable tension, slight contact with the knife is sufficient to permit the knife to cut through the twine which then springs laterally away from the knife and releases the tension about the packing roll and allows the waste to be extruded somewhat on the cut-open side.

The packing roll thus cut comes on out from the underside of the two rollers and is then ready to be carried to any suitable washing mechanism (not here shown).

While we have here shown and described our invention in the one best form as now known to us, it is entirely obvious that structural changes may be made without departing from the spirit of the invention, and we, therefore, do not desire to be limited to that precise form nor any more than may be required by the following claims.

45 We claim:

1. For opening a journal box waste packing roll, a roller, a central ring therearound, said roller having a groove at each side of the ring, means for pressing the roll over said ring, and a knife presented toward said ring over said roll adapted to engage the roll when pressed over said ring.

2. For opening a journal box waste packing roll, a revolvable roller having a pair of grooves therearound with a ring separating the grooves, a second revolvable roller adjacent the first roller having a pair of grooves therearound, and a knife between said second roller grooves having its edge presented toward said first roller ring.

3. For opening a journal box waste packing roll, a revolvable roller having a pair of grooves therearound with a ring separating the grooves, a second revolvable roller adjacent the first roller having a pair of grooves

therearound and a circular knife separating said second roller grooves having its edge presented toward said first roller ring, and means for revolving said rollers in opposite directions.

4. For opening a journal box waste packing roll, a revolvable roller having a pair of grooves therearound with a ring separating the grooves, a second revolvable roller adjacent the first roller having a pair of grooves therearound, and a circular knife separating said second roller grooves having its edge presented toward said first roller ring, the width and depth of said grooves in said rollers being sufficient to permit said roll to be pressed over said ring and to project into said grooves.

5. For opening a used journal box waste packing roll having a confining twine thereabout, a ridge, means for flexing the roll laterally over the ridge to draw the twine taut across the upper side of the roll above said ridge, a knife having a cutting edge presented toward said ridge, and means for relatively moving the roll past the knife to cause the knife to contact with and cut the twine while taut.

6. The method of releasing waste from a used journal box packing roll having confining twine wrapped therearound which embodies those steps of flexing the roll laterally of its length to present an outer taut side and of cutting through the twine on that taut side.

7. The method of releasing waste from a used journal box packing roll having confining twine wrapped therearound which comprises compressing the roll centrally along its length to pull the twine taut across a side thereof and have a central compressed section of waste thereunder with the waste relatively loose to either side thereof, and cutting the twine on the taut side.
